CLEANING DEVICE

Filed Nov. 25, 1925

FIG. 1

FIG. 2

INVENTOR.

ALBERT S. KUX
BY *John Jochum Jr.*
ATTORNEY

UNITED STATES PATENT OFFICE

ALBERT S. KUX, OF CHICAGO, ILLINOIS

CLEANING DEVICE

Application filed November 25, 1925. Serial No. 71,282.

This invention relates to improvements in cleaning devices of the type generally known as vacuum cleaners, and one of the objects of the invention is to provide an improved 5 device of this character which is particularly adapted, though not necessarily limited in its use, for cleaning ovens such as bakers' ovens and the like.

A further object is to provide an improved 10 cleaner of this character which may be employed for cleaning the oven while the latter is hot, and the device includes improved means for handling the hot refuse removed from the oven, and at the same time avoid 15 danger of injuring the apparatus and also the operator thereof.

A further object is to provide an improved 20 portable apparatus of this character which will be of a simple and compact arrangement, effective and efficient in operation and readily 25 adaptable for cleaning parts which it is ordinarily difficult to gain access to.

To the attainment of these ends and the accomplishment of other new and useful objects as will appear, the invention consists 25 in the features of novelty in substantially the construction, combination and arrangement of the several parts hereinafter more 30 fully described and claimed and shown in the accompanying drawing illustrating this invention, and in which

Figure 1 is a view partly in side elevation, partly in section and partly broken away of an apparatus of this character constructed 35 in accordance with the principles of this invention.

Figure 2 is a right hand end elevation of Figure 1.

Referring more particularly to the drawing 40 the numeral 10 designates generally a supporting structure which may be of any desired size and configuration and constructed of any suitable material.

The supporting structure is preferably in 45 the form of a truck like formation having rear wheels 11 and a front or castor wheel 12 swiveled for movement with respect to the supporting structure 10.

In the upper portion of the supporting 50 structure 10 is swiveled an element 13 pro-

vided with spaced bifurcated supports between which a tubular member 14 is disposed. The member 14 is supported by the element 13 preferably by means of trunnions or projections 15 on the tubular member 14 55 which are seated in the respective bifurcated portions of the element 13.

The tubular member 14 is of any desired length and diameter and constructed of any suitable material, preferably metal, and connected to one end thereof is a tubular extension 16. This section 16 may be secured to the section 14 in any suitable manner preferably by means of one end of the member 16 telescoping into the section 14 and a pin 17 and bayonet slot connection 18 is provided for securing these parts together. 60

At the end of the section 16 is arranged a nozzle 19 of any desired construction but is preferably of a configuration to provide 70 an elongated comparatively narrow slot 20 forming the inlet opening to the nozzle.

Brush like members 21 preferably constructed of a substantially rigid material such as wire or the like may be secured to 75 the end of the nozzle 19 and on opposite sides of the inlet opening 20 to project beyond the end of the nozzle for the purpose of facilitating in the removal of any foreign matter which might adhere to the walls of the oven. This material and the refuse in the oven may be removed from the walls thereof or agitated 80 by a manipulation of the nozzle within the oven.

Suction is created in the nozzle through the 85 tubular sections 16 and 14 in any suitable manner preferably by means of a suction creating device 22 in the form of a rotary fan which is arranged within a casing 23. The tubular section 14 is preferably detachably secured to the casing 23 of the fan 22 in any suitable manner such as by means of a pin 90 and bayonet slot connection 24-25.

The fan casing 23 is provided with a discharge outlet opening 26 to which a container 27 is secured preferably by means of a tubular member 28 to which the container is attached and which tubular element is connected 95 with the discharge outlet of the fan cas- 100

ing preferably by means of a pin and bayonet slot connection 29—30.

The container or receptacle 27 is preferably constructed of any suitable fabric which will permit the air currents to pass therethrough and is removably secured to the element 28 in any suitable manner.

The element 28 is of such a size and configuration and the supporting structure 10 is of such a height that the bag or receptacle 27 will be supported above the floor.

Within the bag or receptacle 27 is a strainer or filter 31 which may be constructed of any suitable reticulated material such as metal, 15 preferably in the form of wire gauze and is secured in any suitable manner to the element 28.

The external diameter and the length of the element 31 is considerably less than the 20 internal diameter and the length of the bag or receptacle 27, and is provided for the purpose of not only serving as a filter or strainer for separating the refuse and foreign particles from the air as they are discharged into the bag or receptacle 27, but when this improved apparatus is used for cleaning the ovens when the latter are hot, the refuse which is withdrawn from the oven is also hot, and the element 31 will confine and hold these 25 hot particles.

To discharge these hot particles directly into the bag or receptacle 27 would cause considerable damage to the bag.

By providing the metal strainer or filter 31 it will be manifest that the hot particles will be confined within the metallic portion 31 and they will be held out of contact with the bag or receptacle 27.

The suction creating device 22 may be operated in any suitable manner such as by means of a motor 32 which is mounted upon a suitable support to move with the tubular member 14 and the fan 22, preferably upon the fan casing, the shaft 33 of the motor extending through the wall of the fan casing and to which shaft the fan 22 is connected.

As a means for insulating the motor from the heat of the fan casing and the other parts when hot particles are being removed from the oven, the motor 32 is preferably insulated from the fan casing preferably by means of spacing blocks or elements 34 constructed of any suitable heat insulating material and disposed between the base 35 of the motor and the adjacent wall of the fan casing, thereby not only insulating the motor from the fan casing but also providing a space 36 between the motor and the fan casing through which air currents may circulate.

The motor 32 is driven from any suitable source of power preferably electrically and through the medium of the conductors 37 connected with any suitable source of supply (not shown). Handles 38 and 39 may

be connected with the apparatus for facilitating in manipulating the same.

Obviously any number of sections 14 and 16 may be provided and detachably connected together in any suitable manner so as to 70 lengthen or shorten the same.

The nozzle 19 is also detachably secured to the section 16 in any suitable manner.

In use it will be manifest that by means of the handles 38 and 39 the apparatus may 75 be swung about the pivots 15 and also may be rotated on a vertical axis through the medium of the swivel connection of the element 13 with the support 10. The castor 12 being swiveled to the support 10 also facilitates 80 in the manipulation of the device.

When the suction creating device 22 is in operation and when the nozzle 19 is inserted in the oven, the operator may move the inlet end of the nozzle over the surface of the oven to scrape or remove foreign particles from the wall of the oven and when the suction creating device 22 operates the foreign matter will be drawn into the nozzle through the fan casing and discharged through the element 28 into the metallic filter or strainer 31 where it will be confined. The air currents will pass out of the filter or strainer 31 and into the bag 27 to be discharged therefrom through the walls of the latter.

While this improved apparatus has been described in connection with the cleaning of bakers' ovens, it is obvious that it may be used for many other purposes and for cleaning parts to which ordinarily, access may not be 100 readily had.

Obviously this device may be used for removing foreign matter from flues, and if desired, the nozzle 19 may be removed and any other form of nozzle may be attached 105 to the section 16 or the end of the section 16 may be allowed to remain open when the device is used for cleaning flues.

While the preferred form of the invention has been herein shown and described it is to 110 be understood that various changes may be made in the details of construction and in the combination and arrangement of the several parts, within the scope of the claims, without departing from the spirit of this invention.

What is claimed as new is:—

1. A portable cleaning apparatus for bakers' ovens embodying a supporting structure, a tubular element mounted thereupon for swinging movement on an upright axis and also about a horizontal pivot with respect to the support, a suction nozzle at one end of said element, and a suction creating device at the other end of said element for creating a suction therein.

2. A cleaning apparatus for bakers' ovens embodying a support, a tubular element pivotally mounted upon the support on an upright axis and also on a horizontal pivot

with respect to the support, a suction nozzle supported by one end of the element, a casing supported by the other end of the element and with which casing the element has communication, a discharge outlet leading from the casing, a suction creating device in the casing, a motor mounted upon the casing to swing therewith, and an operative connection between the said motor and the said suction creating device.

10 3. A cleaning apparatus for bakers' ovens embodying a support, a tubular element pivotally mounted upon the support, a suction nozzle at one end of the element, a casing at the other end of the element and with which casing the element has communication, a discharge outlet leading from the casing, a suction creating device in the casing, means for actuating the said suction creating device, and a receptacle connected with the discharge outlet of the casing for receiving the foreign particles and separating them from the air, all of said parts being mounted upon the support for swinging movements on axes intersecting each other.

25 In testimony whereof I have signed my name to this specification, on this 19th day of November, A. D. 1925.

ALBERT S. KUX.
